UNITED STATES PATENT OFFICE

157,334

FENDER GUARD OR SIMILAR ARTICLE

Harry Bookman, Los Angeles, Calif.

Application August 13, 1948, Serial No. 148,096

Term of patent 7 years

(Cl. D14—6)

To all whom it may concern:

Be it known that I, Harry Bookman, a citizen of the United States, residing at Los Angeles, in the county of Los Angeles, State of California, have invented a new, original, and ornamental Design for a Fender Guard or Similar Article, of which the following is a specification, reference being had to the accompanying drawing, forming a part thereof.

Figure 1 is a front view of a fender guard illustrating my novel design.

Figure 2 is an edge view thereof as on a line 2—2 of Figure 1.

Figure 3 is a sectional view as on a line 3—3 of Figure 1.

The essential features of my design are illustrated in full lines.

I claim:

The ornamental design for a fender guard or similar article, substantially as shown and described.

HARRY BOOKMAN.
